Primary Examiner — Elizabeth Albert(74) *Attorney, Agent, or Firm* — Sheridan Ross P.C.(57) **CLAIM**

The ornamental design for a handle for tools, as shown and described.

DESCRIPTION

1. Handle for tools

1.1 is a perspective view of a handle for tools showing the new design;

1.2 is a top view of the handle for tools of 1.1;

1.3 is a left view of the handle for tools of 1.1;

1.4 is a front view of the handle for tools of 1.1;

1.5 is a right view of the handle for tools of 1.1;

1.6 is a back view of the handle for tools of 1.1; and

1.7 is a bottom view of the handle for tools of 1.1.

Figure 1.1 is a perspective view of a handle for tools showing the new design; figure 1.2 is a top perspective view of the handle for tools of figure 1.1; figure 1.3 is a left view of the handle for tools of figure 1.1; figure 1.4 is a front view of the handle for tools of figure 1.1; figure 1.5 is a right view of the handle for tools of figure 1.1; figure 1.6 is a back view of the handle for tools of figure 1.1; figure 1.7 is a bottom view of the handle for tools of figure 1.1.
